COMBINATION TIMER, HANDLE, AND SUPPORT
FOR AN ELECTRIC BAKER OR THE LIKE

Walter E. Moore, St. Louis, Mo., assignor to Knapp-
Monarch Company, St. Louis, Mo., a corporation of Delaware

Filed Mar. 7, 1960, Ser. No. 59,628

Term of patent 14 years

(Cl. D81—10)

Fig. 1 is a perspective view of a combination timer, handle and support for an electric baker or the like showing my new design;

Fig. 2 is a front elevation thereof;

Fig. 3 is a side elevation of the combination timer, handle and support; and

Figs. 4 and 5 are top and bottom views thereof, respectively.

I claim:

The ornamental design for a combination timer, handle and support for an electric baker or the like, substantially as shown.
